UNITED STATES PATENT OFFICE

151,035

DESIGN FOR A FROZEN FOOD STORAGE AND DISPLAY CABINET

Jacob W. P. Fleming, Memphis, Tenn.

Application April 15, 1947, Serial No. 138,402

Term of patent 14 years

(Cl. D80—11)

To all whom it may concern:

Be it known, that I, Jacob W. P. Fleming, a citizen of the United States, residing at Memphis, in the county of Shelby and State of Tennessee, have invented a new, original, and ornamental Design for a Frozen Food Storage and Display Cabinet, of which the following is a specification, reference being had to the accompanying drawing, forming part thereof.

In the drawing, the sole figure is a perspective view of a frozen food storage and display cabinet, embodying my novel design, the ends being similar and the back being plain.

I claim:

The ornamental design for a frozen food storage and display cabinet, as shown.

JACOB W. P. FLEMING.
